UNITED STATES PATENT OFFICE.

GERARD SICKELS, OF BOSTON, MASSACHUSETTS.

DIRECT-ACTING ENGINE.

SPECIFICATION forming part of Letters Patent No. 245,022, dated August 2, 1881.

Application filed May 23, 1881. (No model.)

To all whom it may concern:

Be it known that I, GERARD SICKELS, of Boston, county of Suffolk, and State of Massachusetts, have invented a new and useful Improvement in Fluid Engines or Motors, of which the following description, in connection with the accompanying drawings, is a specification.

My invention relates to a motor to be operated by fluid-pressure; and it consists in a novel construction and combination of parts and method of operating them, as will be hereinafter more fully described.

The movable piston, which also performs, to a certain extent, the function of the usual cylinder of a reciprocating engine, is made as an open rectangular frame, supported on a bed-plate or seat forming the bottom of the cylinder or space in which the fluid-pressure is exerted, and surrounding and inclosing two abutments fixed upon the said bed-plate, which sustain the reaction of the pressure by which the said piston is moved, they forming the fixed boundary at one end of the space within the said piston, and including between them a space or chamber, from which the fluid is led by suitable ports to the space at either side of the said abutments to act on the said piston. A valve placed in the chamber between the abutments, which is herein called the "valve-chamber," controls the passage of the fluid through the said ports, and has connected therewith a plate which fits tightly upon the top of the piston, forming the fourth side to the cylinder in which the fluid is received to act upon the said piston, the said cylinder being rectangular in cross-section, and having its bottom formed by the bed-plate, its sides and ends by the sides and ends of the movable piston, and its top by the said valve-plate. The piston, at the end of its stroke by which one of its ends is brought near to one of the said abutments, engages the said valve-plate and operates the valve, bringing the ports into such connection that the fluid is admitted between the abutment and end of the piston near it and is allowed to pass out from the space between the other abutment and end of the piston which has just been removed therefrom in making its last stroke, so that the piston will now make the stroke in the opposite direction.

The piston-valve and its plate are inclosed

in a chamber in which the actuating-fluid may be directly led, and which may accordingly be called the "pressure-chamber," while below the valve-chamber included between the two abutments an eduction-port or exhaust-passage is placed, the valve being an ordinary **D** slide-valve which alternately connects **U**-shaped ports leading from either side of the valve-chamber to the outside of the abutments with the said exhaust-port. The fluid enters the valve-chamber through passages in the said valve-plate, and thence passes into the cylinder or space within the piston, at one side of one of the abutments, through that one of the said **U**-shaped ports not connected, as just described, by the valve with the exhaust-port.

A latch-bar is employed to maintain the valve in its fixed position during the stroke of the piston, the said latch being operated by the piston near the end of its stroke to release the said valve just before the piston engages and operates it in completing its stroke.

The piston is preferably connected by a suitable piston-rod and connections with a fly-wheel, which properly regulates the length of its stroke.

A motor has previously been made containing a piston composed of a hollow rectangular frame closed at top and bottom by plates and serving as a cylinder for a secondary piston movable therein; but neither of the said pistons is operated by reaction from a fixed abutment within it, as in the present invention.

Figure 1 is a longitudinal section of a motor constructed in accordance with my invention, and Fig. 2 a top view thereof, with the inclosing-case or upper part of the pressure-chamber removed and a portion of the valve-plate broken away to show the parts beneath.

The movable actuating portion or piston *a* of the engine is made as an open rectangular frame, having its opposite inner surfaces, *2*, smooth and parallel, the said piston being mounted on a bed-plate, *b*, provided with two abutments, *c c'*, accurately fitted in the said piston *a*, between the ends of which and the said abutments the fluid operates by its pressure to move the said piston *a*. The spaces included between the said abutments and the ends of the piston thus correspond to the space in the cylinder of a reciprocating engine of

common construction. Two U-shaped ports, *d* *d'*, connect the space included between the said abutments with the space in the piston *a* at either side thereof, and an exhaust-port, *e*, is located between them. The said ports are controlled by a D slide-valve, *f*, having connected therewith a valve-plate, *g*, fitting upon the top of and inclosing the space within the piston *a*. The said valve-plate is provided with induction-ports *h* *h'*, adapted in the movement of the said valve-plate and valve, as hereinafter described, to operate alternately each one to connect the valve-chamber formed between the said abutments with the space external to the said valve-plate and piston, while the other one is closed by one of the said abutments.

The piston *a*, with its abutments *c* *c'*, and valve *f* and valve-plate *g*, are inclosed in a chamber, *i*, mounted upon the bed-plate *b* as its base, in which the actuating-fluid is admitted, it entirely surrounding the said parts.

The valve-plate *g* is provided with suitable lugs or projections, *l*, to be engaged by the piston *a* near the end of its stroke to cause the said valve-plate and valve to accompany it in completing its stroke, thus moving the valve *f* through the valve-chamber between the abutments *c* to change the path of the actuating-fluid.

In order to prevent the valve-plate *g* and valve from moving with the piston *a* before the latter has arrived at the proper position near the end of its stroke, a locking device or latch-bar, *m*, is employed, having locking-shoulders *n* near its ends, the said shoulders being at a distance apart equal to the difference between the entire length of the valve-plate *g* and the length of its stroke. A projection, *p*, at each end of the piston *a* engages an inclined surface, *3*, at the end of the latch-bar *m*, raising its shoulder *n* out of engagement with the end of the plate *g* just before the piston *a* engages the lugs *l* to move the said valve-plate; and when the latter has completed its stroke in one direction by the engagement of the piston *a* with the lug *l* at one end, the holding-point *n* of the bar *m* falls over and engages the valve-plate *g* at its other end. The bar *m* is sufficiently long to engage the ends of the inclosing or pressure chamber *i*, which thus prevents its longitudinal movement.

The piston *a* is connected by a piston-rod, *q*, passing out of the chamber *i* through a suitable stuffing-box, with a cross-head, *r*, guided in its movement by guide-rods *s*, passing through suitable guides on the top of the chamber *i*, and connected by a connecting-rod, *t*, with the crank *u* of a fly-wheel, *v*, from which the power may be transmitted in any usual manner.

The operation is as follows: The parts are shown in the position with the piston near the end of its stroke, the valve *f* and the valve-plate *g* having been moved by the said piston into the position where the inlet-port *h* is closed by the upper surface of the abutment *c* beneath it, and

the space *w* in the piston *a*, into which the actuating-fluid has just been entering, has an exhaust-passage through the port *d*, valve *f*, and exhaust-port *e*, while the induction-port *h'* at 70 the other side of the valve-plate permits the passage of the fluid under pressure from the chamber *i* into the valve-chamber, and thence by port *d'* into the space *y* between the abutments *c'* and piston *a*, from which the fluid 75 has just been exhausted in the last stroke of the said piston. The pressure of the fluid will now cause the piston *a* to make its stroke in the direction of the arrow, just before the end of which the projection *p* will engage the surface 80 3 of the end *n* of the latch-bar *m*, causing it to release the plate *g*, after which the piston *a* will engage the lug *l* of said valve-plate *g*, and in finishing its stroke will move it to the proper position for the valve *f* to connect the 85 ports *d'* and *c*, at the same time opening the valve *h* and closing the valve *h'*, to thus cause the piston to make stroke in the other direction, the latch-bar *m* having engaged the other end of the plate *g* to prevent it from moving 90 with the piston *a* until released by the projection *p*.

The herein-described motor is very simple in construction and positive in operation. The moving parts are entirely surrounded by the 95 fluid by which they are actuated, such arrangement serving to lubricate them, and owing to the particular arrangement the parts will be maintained in proper contact with one another as they wear away.

When stopped on a dead-center the engine may be started in either direction as desired; or a suitable handle may be provided to disengage the latch-bar *m* and shift the valve while the piston is at an intermediate point in 105 its stroke, the direction of which will thus be reversed.

I claim—

1. In a fluid engine or motor, the hollow movable piston and a fixed abutment or partition 110 therein, combined with ports leading to the spaces in the said piston at either side of the said fixed abutment and a valve to control the induction and eduction of the actuating-fluid through the said ports, substantially as described.

2. The bed-plate provided with an abutment fixed thereon, and the movable piston, made as an open rectangular frame mounted upon the said bed-plate and inclosing the said abutment, 120 combined with a plate tightly fitted upon the top of the said piston to inclose a space therein which is divided by the said abutment, substantially as described.

3. The movable hollow piston and two abutments therein, including a fixed space or valve-chamber between them and a variable space between each of them and the adjacent end of the movable piston, combined with induction and eduction ports leading into and out from 125 the said valve-chamber and connecting-ports between the said chamber and space within

the piston at either side thereof, and a valve to govern the said ports, substantially as described.

4. The bed-plate and abutments connected therewith and the hollow piston mounted thereon, combined with the valve and plate connected therewith, and forming the top or cover for the said piston, and adapted to be operated thereby to change the position of the valve, substantially as described.

5. The movable piston and valve-plate, forming a cover therefor and adapted to be operated thereby, combined with the locking device for the said plate, controlled by the said piston, as described, whereby the latter, in making its stroke, first unlocks and then moves the said valve-plate and its connected valve, substantially as and for the purpose described.

6. The bed-plate and its abutments and the hollow piston thereon, and valve and valve-plate, combined with a chamber inclosing the said parts and two ports in the said valve-plate, arranged as described, whereby each one alternately connects the said chamber with the space between the said abutments, while the other is closed by one of the said abutments, substantially as described.

In testimony whereof I have signed my name to this specification in the presence of two subscribing witnesses.
